(57) **CLAIM**

The ornamental design for a vehicle wheel rim, as shown and described.

DESCRIPTION

1.1 is a perspective view of a vehicle wheel rim showing our new design in accordance to a first embodiment;

1.2 is a rear elevation view thereof;

1.3 is a front elevation view thereof;

1.4 is a bottom plan view thereof;

1.5 is a top plan view thereof;

1.6 is a right side elevation view thereof; and

1.7 is a left side elevation view thereof.

2.1 is a rear elevation view of a vehicle wheel rim showing our new design in accordance to a second embodiment;

2.2 is a bottom plan view thereof;

2.3 is a perspective view thereof;

2.4 is a left side elevation view thereof;

2.5 is a front elevation view thereof;

2.6 is a right side elevation view thereof; and

2.7 is a top plan view thereof.
